UNITED STATES PATENT OFFICE

ROBERT C. LIVESAY, OF MOLINE, ILLINOIS, ASSIGNOR TO DEERE & COMPANY, OF MOLINE, ILLINOIS, A CORPORATION OF ILLINOIS

HARVESTER

Application filed November 1, 1928. Serial No. 316,474.

My invention relates to harvesting machinery of the class of harvesters and binders and more particularly to the elevator structure, by which cut grain is conveyed to the binding mechanism, and to means employed for supporting and adjusting the upper elevator to preserve its proper and most effective operative position relative to the lower elevator with which it cooperates in conveying cut grain and delivering it to the binder deck.

Referring to the drawings in which similar numerals indicate identical parts:

Fig. 1 is a rear view, in perspective, of part 15 of a harvester and binder of which sufficient has been shown to illustrate the application of my invention;

Fig. 2 is an enlarged fragmentary view of Fig. 1, in part section, and showing my invention more in detail;

Fig. 3 is a section on the line 3—3 of Fig. 2, and

Fig. 4 is an enlarged detail of part of the adjusting feature of my invention.

In the development of the harvester and binder in which an elevating structure was first employed to receive and convey cut grain from a platform conveyor and deliver it to the binding mechanism, the structure 30 comprised an upper and a lower canvas conveyor operating over rolls rigidly supported in the front and rear parts of the elevator frame. In this construction, the front and rear of the space between the conveyors was 35 closed and consequently the length of grain which could be harvested and bound was limited. To overcome this objectionable feature and accommodate a harvester and binder to any length of grain, a frame was developed in which the front of the upper and lower elevators was supported, as at present, but the rear of the lower elevator was supported rigidly on the harvester frame, and the rear of the upper elevator was supported 45 on an arched seat support. This construction provided an open rear to the space between the upper and lower elevators and made it possible to harvest grain of any length and successfully elevate it to the binder, the upper elevator being attached to and

supported on the seat support only. Because of the rough and arduous work of harvesting, it became apparent that the upper elevator, supported at only one point rearwardly, was liable to sag at its rear upper end and destroy the proper relation of the two elevators for efficient operation, a defect which demanded a remedy operable to overcome any sag that might occur, a demand that has been met by various devices possessing features of adjustment by which the proper position of the elevator can be maintained; and to this class of devices my invention belongs, and has for its object to provide a simple and economical device by the adjustment of which the upper elevator can be kept in proper operative position relative to the lower elevator, a device which is easily and readily adjustable by one person and very effective for the purpose for which it was designed.

As stated sufficient of a harvester and binder is shown to illustrate the application and operation of my invention, and it includes parts 1 of the harvester frame supporting the rear lower elevator frame 2. An arched seat beam 3, of a common type, is secured on the harvester frame and mounted thereon is a seat support 4 having a spring 5 interposed between the beam and support, both the support and spring being secured to the beam 3 by bolts 6 and 7. Rigidly secured, stubbleward, on the rear of the frame 8 of the upper elevator 9, is a bracket 10 having a rearwardly extending part 11 provided with an eye for reception of a rod or bar 12, which is adapted to be moved lengthwise in said eye by operation of a nut 13 on the end of the rod and on the stubbleward side of the part 11, the end of the rod being threaded; a jam nut 14, on the opposite side of the part 11, and on the rod 12, is utilized to hold the rod from longitudinal movement. The opposite end of the rod 12 is secured to the seat beam 3 by the bolt 6.

A vertically disposed link 15 is rigidly secured on the beam 3 by a bolt 16 extending horizontally through the beam 3 and transversely thereof; the link 15 extends downwardly and is bent to prevent a flat surface to the rear of the upper elevator frame. On

the lower end of the link 15, and preferably integral therewith, is a part 17 provided with a slot 18, alined with the inclination of the frame 8, through which extends a bolt 19 on the frame 8 by which the link 15 is secured to the frame 8 and held in place by a nut, a serrated washer being interposed between the nut and the face of the part 17, which is also serrated, as shown. Opposite the link 15 and rigidly secured on the beam 3 by the bolt 6 is a link 20 extending downwardly transversely of the link 15 to which it is attached by a rivet 21. The lower end of the link 20 forms an eye 22 through which extends a rod 23 on the end of which, and on the stubbleward side of the eye 22, is a nut 24. The lower end of the rod 23 is provided with an eye by which said rod is secured to the crank end of the rod of the canvas tightener.

20 The parts as shown and described are in perfect operative position. Now, presuming that the upper elevator 9 has sagged at its upper end and I desire to remedy the defect, I loosen the jam nut 14, and the nut 19. If the rear upper end of the elevator 9 is too close to the lower elevator, I shorten the connection with the rod 12 by turning the nut 13 in the right direction until the required adjustment has been made after which the jam nut 14 is operated to hold the parts in the new position and the nut 19 is tightened. If the elevator 9 has a longitudinal sag, it is readily corrected by loosening the nut on the bolt 19 and the jam nut 14; the adjustment is effected by operation of the nut 24, the bolt 19 moving freely in the slot 18. Upon the proper position of the elevator 9 being attained, the nuts loosened are again tightened. During the adjustments, for either of the purposes stated, the elevator 9 is firmly supported on the seat beam 3; consequently, either or both adjustments can be readily and quickly effected by one operator.

What I claim is:

- 45 1. In a harvester binder, the combination with upper and lower elevator frames and a support, of a bar attached to the support extending stubbleward and adjustably connected to the upper elevator frame, a support for said frame attached to the support extending downwardly therefrom and connected to said frame, and means operative to adjust said frame longitudinally on said support.
- 50 2. In a harvester binder, the combination with upper and lower elevator frames and a support, of a bar attached to the support extending stubbleward and adjustably connected to the upper elevator frame, a support for said frame attached to the support extending downwardly therefrom and connected to said frame, and means connected with said frame and to said support and operative to adjust said frame longitudinally.
- 55 3. In a harvester binder, the combination with upper and lower elevator frames and a

support, of a bar attached to the support extending stubbleward and adjustably connected to the upper elevator frame, a support for said frame comprising links attached to said support and extending downwardly, one of said links adjustably connected to said frame, and a bar extending longitudinally of said frame and attached thereto and adjustably connected to the lower end of the second link. 70

4. In a harvester binder, the combination with upper and lower elevator frames and a support, of a bar attached to the support extending stubbleward and adjustably connected to the upper elevator frame, a support for said frame comprising links attached respectively to opposite sides of said support and extending downwardly, one of said links adjustably connected to said frame, the second link extending downwardly in a stubbleward direction and rigidly secured to the first link, and a bar connected with said frame and adjustably connected to the lower end of the second link. 75

5. In a harvester binder, the combination with upper and lower elevator frames and a support, of a bracket on the upper frame, a bar attached to the support extending stubbleward and adjustably connected to said bracket, a support for said upper frame comprising links attached respectively to opposite sides of the support and extending downwardly, one of said links perpendicularly disposed and having its lower end adjustably attached to said frame, the second link extending diagonally downwardly over the first link and rigidly secured thereto, and a bar extending longitudinally of said frame and attached thereto and adjustably connected to the lower end of the second link. 90
